ABRASIVE UNIT

Joseph S. Kozacka, Chicago, Ill., assignor to Skil Corporation, Chicago, Ill., a corporation of Delaware

Application February 19, 1958, Serial No. 716,118

6 Claims. (Cl. 51—194)

The present invention is directed to a new and improved abrasive unit of the type particularly adapted for use in leather working such as carried out in the manufacture of shoes.

In shoe manufacture and repair work, a series of cylindrical abrasive units are mounted on a single rotatable shaft in spaced end-to-end relation. Normally, the abrasive properties of the different units will vary from coarse to fine to provide a series of units capable of completing the different operational stages of leather shaping and finishing. The mounting of a plurality of abrasive units on a single shaft not only allows savings in the use of a single power source and drive connection for rotating the shaft, but also provides for efficiency in leather shaping operations by allowing the operator to quickly move from one abrasive unit to another for variable abrasive action. The mounting of a plurality of spaced abrasive units on a single shaft is also advantageous even if the individual abrasive units do not vary in abrasive action, as a plurality of operators can utilize the same power source and equipment in carrying out leather shaping operations.

The abrasive material generally used in the past is in the form of flexible paper such as sandpaper, emery paper, garnet paper, aluminum oxide paper, and the like. Rapid deterioration of the abrading or scoring surface of such material is prevalent resulting in substantial economic losses due to the necessity for replacing the material. Even though sandpaper and related articles are relatively inexpensive, they constitute a distinct economic disadvantage insofar as the overall finishing processing is concerned. Such abrading and scoring articles are relatively low in efficiency, particularly when applied to surface finishing of relatively tough or hard materials.

As disclosed in co-pending applications, Serial No. 676,766, filed August 7, 1957, and Serial No. 676,774, filed August 7, 1957, an improved form of abrasive element is now available wherein the working surface thereof is coated with an improved abrasive such as sintered tungsten carbide. The new abrasive material may be readily applied to a rigid base such as a section of tubing to supply an abrasive element capable of long-life, efficient operation. With the mounting of the abrasive material on a rigid tube member the same can be concentrically mounted about a shaft for rotation therewith in the forming of an assembly of a plurality of such units mounted on a single shaft as described above. It will be appreciated however, that if tubular abrasive elements of this type are mounted on a single shaft in spaced relation therewith, it would be necessary to thread the elements onto the shaft for fixing thereto in the particular order desired. Ready rearrangement of the various units would be difficult in the respect that it would be necessary to remove the endmost units in order to gain access to an intermediate unit for rearrangement of the same along the shaft or for replacement of various parts thereof. In certain instances, the units

2

removed in order to gain access to an intermediate unit would not need maintenance or replacement of parts thereof and the time and effort consumed in dismounting and subsequently remounting these units would materially add to the overall time during which the entire assembly would be out of operation.

It is an object of the present invention to provide a new and improved abrasive unit utilizing a rigid abrasive element for mounting concentrically relative to a rotatable shaft or the like, the abrasive element being driven by mounting members constituting a part of the unit and being capable of providing extended and efficient abrasive action for material finishing processing.

Another object of the present invention is to provide a new and improved abrasive unit incorporating therein certain structural features allowing ready mounting or replacement of the abrasive element thereof without disturbing adjacent units mounted on a common shaft.

Still a further object is to provide a new and improved abrasive unit assembly of uncomplicated structural arrangement, the assembly including abrasive element mounting features allowing for quick and efficient abrasive element mounting or replacement without actual removal of any portion of the unit from the shaft on which it is mounted with the exception of the abrasive element to be replaced.

Still another object taken in conjunction with the foregoing is to provide an improved form of abrasive unit in which the abrasive element thereof is not only readily mountable or replaceable without dismounting the permanent mounting elements of the unit from the shafts, but the permanent mounting elements of the unit are adapted to efficiently mount abrasive elements of variable length, the relative location of the mounting elements being readily varied while retained on the shaft to accommodate different lengths of abrasive elements.

Other objects not specifically set forth will become apparent from the following detailed description made in conjunction with the drawings wherein:

Fig. 1 is a fragmentary perspective of a typical installation of a plurality of abrasive units of the present invention;

Fig. 2 is an enlarged perspective of the removable semi-cylindrical abrasive element sections of the unit of the present invention;

Fig. 3 is a fragmentary, partly sectioned elevation of the assembled unit;

Fig. 4 is a longitudinal section of the unit;

Figs. 5 and 6 are side and front elevational views, respectively, of one of the mounting elements forming a part of the unit;

Figs. 7 and 8 are side and front elevational views, respectively, of another of the mounting elements of the unit;

Figs. 9 and 10 are elevation and front views, respectively, of still another mounting element of the unit; and

Figs. 11 and 12 are elevation and front views, respectively, of still another mounting element of the unit.

In Fig. 1, a typical assembly of a plurality of abrasive units 15 of the present invention is illustrated, the units being mounted in spaced end-to-end relation on a common rotatable shaft 16. While the shaft is only partly shown it will be appreciated that the same is suitably rotatably driven by a known type of drive arrangement resulting in the rotation of the units 15 in the same direction at the same speed. Referring to Figs. 1 and 2, the abrasive element 17 of each of the units 15 is in the form of a two-part sleeve including semi-cylindrical sleeve sections 18 and 19 of identical construction and mounted to define therebetween a cylinder received concentrically about the shaft 16.

The abrasive element 17 may be formed by longitudi-

nally bisecting a length of pipe, such as seamless steel tubing, the pipe being of any desired diameter. The pipe length is sub-divided so as to define oppositely positioned slots 20 which are preferably of a width of about $\frac{1}{16}$ of an inch, these slots being maintained upon mounting of the sleeve sections 18 and 19 in a manner to be described to, in effect, provide a slotted cylinder. The outer surface of each sleeve section 18 and 19 is coated with a suitable abrasive such as sintered tungsten carbide as disclosed in the aforementioned copending applications. The inner surfaces at the ends of the sleeve 17 are machined to define an annular sleeve mounting surface 21 of reduced thickness which terminates inwardly with a radial annular shoulder 22. The outer surface end margins of the sleeve 17 are provided with a mounting bevel 23 and in this manner the abrasive sleeve 17 is completed and ready for installation.

The sleeve mounting elements of the unit 15, as particularly shown in Figs. 3 and 4, include spaced end members 24 and 25, an abrasive section end engaging collar 26 and a clamping ring 27. These elements are illustrated in detail in Figs. 5-12, respectively.

Figs. 5 and 6 illustrate the end member 24 as including an outer axially extending hub portion 28 provided with a central bore 29 and being provided with an inwardly positioned, enlarged radial portion 30 for mounting one end of the abrasive sleeve 17. The inner radial face of the radial portion 30 is provided with an axially projecting shoulder 31 of reduced diameter which is aligned with an annular recessed groove 32 of wedge shape into which the bevel end 23 of the sectionalized sleeve 17 is received as shown in Figs. 3 and 4. The inner mounting surface 21 of the sleeve 17 is received in engagement with the shoulder 31 of the end member 24 with the bevel 23 being received within the groove 32. The inner radial surface of the portion 30, as well as the shoulder 31, are provided with oppositely positioned, radially inwardly directed drilled openings 33 into which drive pins 34 are received as shown in Fig. 4. The outer end portions of the drive pins 34 project outwardly of the shoulder 31 and are received within the slots 20 between the side margins of the sleeve sections 18 and 19. The drive pins 34 are held in sleeve engaging position by set screws 35 advanced into tapped holes 36 which extend in an axial direction through the radial portion 30 of the end member 24.

Referring particularly to Fig. 4, the end member 24 is fixed on the shaft 16 by set screws 37 received in radially directed tapped holes in the axial hub portion 28 thereof and the end member 24 rotates with the shaft. The drive pins 34 rotate with the end member 24 and are held in torque transmitting engagement with the sleeve sections 18 and 19 by the set screws 35. Thus, one end of the sleeve 17 is engaged by the end member 24 for rotation therewith and the shaft 16, the sleeve being readily demountable from the end member 24 by axial movement of the sleeve away from the inner surface thereof to withdraw the beveled end from the groove 32 and separate the drive pins 34 from the slots 20.

The end member 25, as particularly shown in Figs. 7 and 8, is formed from a series of step-like annular portions 38, 39 and 40 with each being of progressively greater diameter in an inwardly direction. The greatest diameter, however, being such that the end member 25 is readily received within the sleeve 17 upon mounting the same on the shaft 16 through its central bore 41 as shown in Fig. 4. The innermost end of the end member 25 terminates in a radially enlarged shoulder 42 telescoped within the sleeve 17 with the outer surface of the portion 40 being provided with oppositely positioned slots or grooves 43. The outer periphery of the intermediate portion 39 is threaded and the outermost portion 38 of least diameter is provided with a plurality of tapped holes 44 in which set screws 45 are received to fix the end member 25 to the shaft 16 for rotation therewith.

Received about the innermost portion 40 of the end member 25 is the abrasive element holding collar 26, the structural details of which are particularly shown in Figs. 4, 9 and 10. The inner diameter of the collar 26 is slightly greater than the outer diameter of the portion 40 of the end member 25 to allow axial movement of the collar relative to the end member 25. The collar 26 is provided with an outer, radially enlarged portion 46 and an inner, radially reduced portion 47 having aligned with the outer surface thereof an annular wedge-shaped groove 48 into which the remaining bevelled end of the sleeve 17 is received. The outer surface of the portion 47 is provided with oppositely positioned, radially inwardly directed drilled holes 49 into which drive pins 50 are received. The drive pins are held in operative positions by axially directed set screws 51 which are introduced into tapped holes 52 extending from the outer radial face of the collar 26. As shown in Fig. 4, the drive pins 50 are of sufficient length to have their inner ends received in the oppositely positioned grooves or slots 43 of the end member 25 to provide a type of spline connection to cause rotation of the collar 26 with the end member 25 and shaft 16 while allowing axial movement of the collar 26 relative to the end member 25. The outermost ends of the drive pins 50 are received in the slots 20 of the sleeves 17 for torque transmission thereto in the same manner as described in connection with the drive pins 34.

To complete the assembly, the clamping ring 27, illustrated in detail in Figs. 11 and 12, is utilized to maintain the collar 26 in mounting and torque transmission engagement with the adjacent end of the sleeve 17. The clamping ring 27 is provided with an outer threaded bore 53 which communicates with an inner enlarged bore 54. The ring 27 is threadedly advanced onto the portion 39 of the end member 25 with the threaded bore 53 being engaged with the threads carried by the outer surface of the portion 39. The inner bore 54 is of sufficient diameter to clear the outer surface of the portion 40 of the end member 25 with the inner radial face of the ring engaging the outer radial face of the collar 26. In this manner the ring 27 is threadedly advanced into engagement with the collar 26 to clamp the same in end support and torque transmission relationship with the element 17. The ring 27 holds the collar 26 against axial movement along the end member 25 and, in addition, clamps the opposite end of the abrasive element 17 into supported and torque transmission engagement with the opposite end member 24.

Following operative mounting of the abrasive element 17 and proper clamping of the assembly by advancement of the ring 27, which advancement is enhanced for the knurled outer surface thereof, the position of the ring 27 is fixed by the tightening of set screws 55 received in radially inwardly directed tapped holes 56 formed in the ring 27 in communication with the bore 53 thereof. In order to protect the threads formed on the outer surface of the portion 39 of the end member 25 against the clamping action of the set screws 55, soft metal plug inserts 57 are preferably received within the tapped holes 56 and the set screws 55 work against these plugs with the latter engaging the threads of the end members 25.

From the foregoing description of the structural features and operative mounting of the abrasive unit of the present invention, it will be appreciated that the operative length of the unit can be varied considerably by merely changing the space between the end members 24 and 25. For replacement of an abrasive element, it is necessary merely to loosen the set screws 55, threadedly retract the clamping rings 27, slidingly retract the holding collar 26 to an extent that the same becomes disengaged from the adjacent end of the abrasive element 17 and remove the sectionalized abrasive element out of engagement with the end members 24 and 25. In this manner the fixed positioning of the end members 24 and 25 need not be varied and none of the abrasive element mounting mem-

bers is removed from the shaft 16. The abrasive element 17 can be replaced without disturbing operative mounting of adjacent units thus materially reducing the period of inoperativeness of the entire assembly during maintenance of a single unit thereof.

While the foregoing description has been directed to the use of the abrasive unit 15 of the present invention in an assembly wherein a plurality of such units are mounted in spaced relationship on a single shaft, it will be understood that the important structural features of the unit in connection with ready replacement of the abrasive element thereof can advantageously be utilized in a single unit assembly. In this respect, replacement of the abrasive element does not require actual dismounting of any of the permanent elements from the shaft or spindle carrying the unit. Still further, while the abrasive unit has particular utility in leather shaping and processing, it will be appreciated that the same may be used for many different purposes in line with known uses of abrasive units.

Obviously, certain modifications and variations of the invention as hereinbefore set forth may be made without departing from the spirit and scope thereof, and therefore only such limitations should be imposed as are indicated in the appended claims.

I claim:

1. An abrasive unit for mounting on a rotatable shaft, said unit including a plurality of arcuate abrasive sleeve sections combined to define an annular sleeve which is held and drive connected at opposite ends thereof by end members arranged for concentric mounting about a shaft for rotation therewith, one of said end members including an axially movable sleeve section clamping ring drive connected with said one end member and holding said sections in operative position spaced relative to the shaft, and position fixing means for releasably holding said clamping ring in axially advanced position on said one end member to hold said sections while allowing axial retraction of said clamping ring for dismounting of said sections from said end members.

2. An abrasive unit mounted on a rotatable shaft, said unit including a plurality of arcuate abrasive sleeve sections combined to define an annular sleeve concentrically about said shaft and releasably held and drive connected at opposite ends thereof by end members fixed for rotation with said shaft, one of said end members including an axially movable sleeve section clamping ring drive connected with said one end member and holding said sections in operative position spaced relative to the shaft, and position fixing means for releasably holding said clamping ring in axially advanced position on said one end member to hold said sections while allowing axial retraction of said clamping ring for dismounting of said sections from said end members.

3. A plurality of abrasive units mounted on a rotatable shaft in spaced end-to-end relation, each of said units including a plurality of arcuate abrasive sleeve sections combined to define an annular sleeve concentrically about said shaft and releasably held and drive connected at opposite ends thereof by end members fixed for rotation with said shaft, one of said end members including an axially movable sleeve section clamping ring drive connected with said one end member and holding said sections in operative position spaced relative to the shaft, and position fixing means for releasably holding said clamping ring in axially advanced position on said one end member to hold said sections while allowing axial retraction of said clamping ring for dismounting of said sections

from said end members independent of the other units on said shaft.

4. An abrasive unit mounted on a rotatable shaft, said unit including a pair of substantially semi-cylindrical abrasive sleeve sections mounted concentrically about said shaft at the ends thereof by end members fixed to said shaft, said sections being spaced from one another along the side margins thereof to define axial slots in which radially directed drive pins are received, said drive pins being removably carried by said end members, one of said end members including an axially movable sleeve section clamping ring for holding said sections in operative position, and position fixing means for releasably holding said clamping ring in axially advanced position on said one end member to hold said sections while allowing axial retraction of said clamping ring for dismounting of said sections from said members.

5. An abrasive unit mounted on a rotatable shaft, said unit including a pair of substantially semi-cylindrical abrasive sleeve sections mounted concentrically about said shaft at the ends thereof by end members fixed to said shaft, said sections being spaced from one another along the side margins thereof to define axial slots in which radially directed drive pins are received, said drive pins being removably carried by said end members, the drive pins of one of said end members being received in axially extending grooves for axial displacement out of said slots for dismounting of said sections and for torque transmission to said sections while received in said slots, said one end member receiving thereabout an axially movable sleeve section clamping ring for holding said sections and the drive pins in said grooves in operative positions, and position fixing means for releasably holding said clamping ring in axially advanced position on said one end member to hold said sections while allowing axial retraction of said clamping ring for dismounting of said sections from said end members.

6. An abrasive unit mounted on a rotatable shaft, said unit including a pair of substantially semi-cylindrical abrasive sleeve sections mounted concentrically about said shaft at the ends thereof by end members fixed to said shaft, said section being spaced from one another along the side margins thereof to define axial slots in which radially directed drive pins are received, said drive pins being removably carried by said end members, one of said end members being of reduced diameter to have the inner end portion thereof telescopically received within said sections, the outer periphery of said one end member having a pair of oppositely positioned grooves over which an axially slid able section end engaging collar is received, the driven pins of said one end member being mounted in said collar with the outer ends thereof received in said slots and the inner ends thereof received in said grooves, an axially movable collar clamping ring received about said one end member axially outwardly of said collar, and position fixing means forming a part of said clamping ring to releasably hold the same relative to said one end member in abutment with said collar to engage said collar and said drive pins with said sections.
